DESIGN FOR A RADIO CABINET

Benjamin S. Nash, Short Hills, N. J., assignor to
Philco Radio & Television Corporation, Phila-
delphia, Pa., a corporation of Delaware

Application January 23, 1936, Serial No. 60,751

Term of patent 14 years

To all whom it may concern:

Be it known that I, Benjamin S. Nash, a citizen
of the United States, residing in Short Hills, coun-
ty of Essex, State of New Jersey, have invented
a new, original, and ornamental Design for a
Radio Cabinet, of which the following is a speci-
fication, reference being had to the accompa-
nying drawings, forming part thereof, in which:—

Figure 1 is a perspective view of the cabinet;
Fig. 2 is a side elevational view of the same;

Fig. 3 is a fragmentary sectional view of the
central front panel between the lines 4—4 and
A—A of Fig. 2, this view being taken along line
3—3 of Fig. 4; and

Fig. 4 is a sectional view taken along line 4—4
of Fig. 2.

I claim:

The ornamental design for a radio cabinet, sub-
stantially as shown.

BENJAMIN S. NASH.
